(57) CLAIM

The ornamental design for a confectionary stand, as shown and described.

DESCRIPTION

FIG. 1 is a perspective view of a confection display package; FIG. 2 is a front view thereof, the rear side view being identical;

FIG. 3 is a left side view thereof, the right side view being identical;

FIG. 4 is a bottom view thereof; and,

FIG. 5 is a top view thereof.

The broken lines shown in FIG. 1 are for illustrative purposes only and form no part of the claimed design.
